United States Patent Office

Des. 216,610
Patented Feb. 17, 1970

216,610

FOLDABLE SUNNING MAT

Leonore D. Stiver, 1630 A St., San Diego, Calif. 92101

Filed May 1, 1968, Ser. No. 11,730

Term of patent 14 years

Int. Cl. D6—08

U.S. Cl. D92—2

Fig. 4.

Fig. 3.

Fig. 2.

Fig. 4.

I claim:

The ornamental design for a foldable sunning mat, substantially as shown.
